United States Patent Office.

H. SCHUYLER ROSS, OF NEW YORK, N. Y., ASSIGNOR TO CHARLES G. ROSS,
AND HENRY B. EELLS.

Letters Patent No. 78,395, dated May 26, 1868; antedated May 14, 1868.

IMPROVEMENT IN STEAM WATER-EJECTORS.

The Schedule referred to in these Letters Patent and making part of the same.

TO ALL WHOM IT MAY CONCERN:

Be it known that I, H. SCHUYLER Ross, of New York city, in the county and State of New York, at present in the Engineer Corps of the United States Navy, have invented new and useful Improvements in Steam Water-Ejectors; and I do hereby declare that the following is a full, clear, and exact description of the same, reference being had to the accompanying drawing, forming part of this specification.

This invention consists in the combination, with an auxiliary receiving-pipe in steam water-ejectors, of an annular or surrounding steam-way or nozzle, so arranged relatively to each other, that the steam employed for forcing forward the water will not only act upon the water rising in the auxiliary receiving-pipe, but also upon the water in a surrounding pipe or reservoir; it also consists in such construction of the nozzle steam-pipe or way that the same, when forced forward or backward, or by other movement, will regulate or entirely cut off the flow of steam therefrom, whereby a great saving in steam is effected.

In the accompanying drawing—

Figure 1 is a longitudinal central section of my invention.

Figure 2 is a similar view of my invention applied to a style of ejector now in use.

Figure 3 is a similar view of my invention, considerably enlarged.

A, (refer to fig. 1,) designates the discharge-pipe, and B the suction-pipe, the latter branching off from the former, and describing something of an angle therewith.

C designates a steam-way or nozzle, which, in the present instance, is let into the force-pipe A, at the angle formed by it and the suction-pipe B. The walls of this nozzle are designated by letters *a a*, and the space within these walls is an annular steam-chamber or way, into which steam is conducted through a pipe, D.

E is an auxiliary suction-pipe, whose upper end is let into the chamber or nozzle C. Where the pipe E enters said nozzle, I employ a stuffing-box, to form a steam-tight joint. This auxiliary suction-pipe is constructed and arranged so that by a longitudinal movement thereof the quantity of steam issuing from the steam-nozzle may be regulated as desired. A screw-thread, *b*, cut upon the pipe, and working in a nut, *c*, is employed in the present instance, and a wheel, *d*, for turning the pipe E, in order to move it longitudinally.

The top edges of the walls *a a*, of the steam-chamber nozzle or way, are bevelled inward, and the top edge or end of the suction-pipe E is bevelled outward in a corresponding manner, as will be seen by reference to fig. 1. Now, by forcing the suction-pipe E upward, till it strikes the bevelled top edge of the walls *a a*, the flow of steam will be entirely cut off. It is therefore evident that the quantity of steam allowed to issue from the nozzle C can be regulated as desired, by merely throwing up or down the suction-pipe E.

In fig. 2, substantially the same kind of a steam water-ejector is shown, except that the force-pipe A has two suction-pipes, B B. In this example, as will be seen plainly in the enlarged view, fig. 3, the top end of the suction-pipe E is bent inward, and the upper end of the nozzle corresponds therewith, and the flow of the steam is regulated by a longitudinal movement of the suction-pipe E, as before described.

I will here remark, that the tops of the auxiliary suction-pipe and the steam-nozzle, may be constructed in various ways, so as to enable the regularity of the flow of steam, and I do not therefore limit myself to the construction as herein shown.

A lining or coating, of felt, *e*, fig. 3, or other non-conductor of heat, is placed upon the surface of the steam-nozzle pipe or way, where it is exposed to the water. A similar lining or coating, *f*, may also be employed upon the inner surface of the auxiliary suction-pipe. By the employment of such lining or coating in combination with such exposed surfaces, condensation of steam is prevented in a great degree.

By the above improvements in steam water-ejectors, I gain many advantages, among which may be recited the economizing of steam, and the gaining of an independent stream of water, acted upon by the same steam, which forces the water out of an ordinary steam ejector.

I am aware that in the "Giffard ejector" a plug is used for closing the steam-way, but I do not use a plug, but a pipe, which in itself serves an important purpose, as before recited.

What I claim as my invention, and desire to secure by Letters Patent, is—

1. The arrangement of the water-pipe or conductor E, in such relation to the steam-pipe or jet C, that the discharge-end of such water-pipe shall open or discharge within the steam-pipe or jet, substantially as herein specified.
2. The arrangement of the water-pipe or conductor E, so that by a longitudinal movement of the said water-pipe or conductor, the flow of steam from the steam-pipes or jet C, may be entirely shut off or regulated, substantially as herein specified.

H. SCHUYLER ROSS.
